ELECTRIC PLUG AND RECEPTACLE

Charles J. Saunders, Los Angeles, Calif.

Application July 19, 1938, Serial No. 219,991

2 Claims. (Cl. 173—330)

My invention relates to electrical connectors and has particular reference to a plug and receptacle adapted to readily permit connection of portable electrical appliances to an electric supply circuit.

To provide for the ready connection of portable electrical appliances to supply circuits in homes, stores or other buildings, it is the usual practice to provide the appliances with a flexible electric cable to one end of which is secured a connector plug having metal terminals thereon adapted to be inserted into terminal openings in a receptacle which in turn is permanently and stationarily located in the building and is permanently connected to the supply circuit or wiring within the building or into the terminal openings of an adaptor which is screwed into a socket.

The ordinary construction of such plugs and receptacles is such that the prongs or metal terminals project from a handle portion in such a manner as to permit them to be inserted into predetermined terminal openings in the receptacle, making it necessary to accurately align the ends of the plug terminals with the reception openings before the plug may be inserted. It frequently occurs that connection of the appliances must be made in the dark, or the location of the receptacle is such that it is impossible to see the terminal openings therein so that it is necessary to make several attempts to align the plug terminals with the openings before the connections may be completed.

It is therefore an object of my invention to provide a plug and receptacle so constructed that the front surface of the receptacle constitutes a guide for the plug, automatically aligning the axis of the plug with the center of the receptacle.

It is another object of my invention to provide a plug and receptacle of the character set forth in the preceding paragraph wherein the mere pressing of the plug against the front face of the receptacle will center the plug with the receptacle, making it necessary only to turn the plug in its centered position to accurately align the receptacle openings with the plug terminals.

Another object of my invention is to provide a plug and receptacle of the character set forth wherein the plug is provided with an outwardly projecting guide stem and in which the receptacle is provided with an axially aligned guide bore for receiving the stem to constitute a guide for the insertion of the plug in the receptacle and in which terminal openings are so arranged with respect to the guide bore that a slight twisting movement of the plug after the stem has been

inserted into the guide bore aligns the plug terminals with the receptacle terminals.

Another object of my invention is to provide a plug connector in which the metal terminals extend along and are reinforced by a guide stem 5 extending between them.

Another object of my invention is to provide a plug receptacle which includes terminal connector members of such length as will permit great flexibility to prevent damage thereto by repeated 10 insertion of the plug into electrical contact therewith.

Other objects and advantages of my invention will be apparent from a study of the following specifications, read in connection with the accompanying drawing, wherein—

Fig. 1 is a perspective view of the receptacle construction, in accordance with my invention, applied to the usual type of wall receptacle installation.

Fig. 2 is a perspective view of a connector plug constructed in accordance with my invention and adapted for use with the receptacle shown in Fig. 1.

Fig. 3 is a vertical sectional view taken along line III—III of Fig. 1 showing the internal construction of the wall receptacle and showing a plug inserted therein.

Fig. 4 is a side elevational view of the receptacle body shown in Fig. 3.

Fig. 5 is a detail sectional view taken along line V—V of Fig. 4.

Fig. 6 is a detail sectional view taken along line VI—VI of Fig. 4.

Fig. 7 is a detail sectional view of the plug 35 constructed in accordance with my invention, the section being taken along line VII—VII of Fig. 2.

Referring to the drawing I have illustrated, particularly in Fig. 3, a wall receptacle A constructed in accordance with my invention adapted to be mounted in the conventional junction box 1 employed in the ordinary wiring of buildings. The junction box 1 may be a metal box of the conventional type secured immediately to the rear of the surface of a wall 2 and to which a 45 conduit or other form of protective sheathing 3 may be coupled which carries conductor wires 4 and 5 for supplying electric current to the receptacle A.

The receptacle A includes a body member 6 50 illustrated as comprising a cylindrical piece of suitable insulating material adapted to be secured to a supporting strip 7 as by means of pressing the same into a circular opening 8 in the strip and either holding the same therein 55

by a pressed fit between these members, or, if desired, screws 9 extending through ears 10 on the strip and into threaded engagement with the body 6 may be employed. As will be understood by those skilled in the art, the strip 7 is secured by means of screws 11 to threaded ears 12 on the box 1.

The forward end of the body 6 is provided with a radially extending flange 13 preferably adapted to rest against the outer surface of the supporting strip 7 so that a relatively large diameter cone-shaped depression 14 may be formed in the outer face of the body 6, the apex of the cone leading into a cylindrical bore 15 disposed along the central axis of the body 6. A pair of oppositely disposed radial slots 16 and 17 extend for a considerable distance from the front face of the body 6 and communicate with the central bore 15 to provide terminal openings adapted to receive plug terminals formed upon and constituting part of a plug connector B to be herein-after more fully described.

The receptacle terminals may be provided, illustrated herein as comprising short strips of suitable metal 18 and 19, each of the terminals 18 and 19 having an elongated body portion, one end of which is secured as by a screw 20 to the outer surface of the body 6 near the extreme rear end of the body so that the engaging end 21 of the terminal strip 18 may flex through relatively great limits without permanent distortion of the strip. The engaging end of the strips 18 and 19 are illustrated as being bent about a relatively sharp radius to present a smooth curve to the plug terminals, the engaging ends 21 of the strips 18 extending into radial extensions 22 of the recesses 16 and 17 respectively.

By referring particularly to Fig. 5 it will be noted that the strips 18 and 19 are provided with lateral extensions 23 through which is threaded a screw 24 and between which the ends of the wires 4 and 5 may be clamped to make connection therewith. The receptacle so constructed and assembled upon its strap 7 may be secured to the box 1 with the outer surface of the strap 7 approximately flush with the wall surface 2 and the usual face-plate 25 may be attached in the conventional manner by means of screws 26.

The plug B, which may be used with my receptacle, may comprise a handle or body portion constructed of complementary halves 27 and 28, one of these halves including recesses 29 and 30 disposed upon diametrically opposing sides of a cylindrical stem-like portion 31 which projects forwardly of that half of the body. Secured as by means of screws 32 to this half of the body portion are a pair of strips of metal 33 and 34 which extend through the recesses 29 and 30 and along the forwardly projecting stem 31, the strips 33 and 34 constituting the plug terminals 18 and 19. While the shape of the strips 33 and 34 is not material, I prefer to construct them of strips of relatively heavy brass or similar material and dispose them on edge along the stem 31. The outer ends of each of the strips may be bevelled as indicated at 35 to engage and flex the bent ends of the receptacle terminals outwardly as the plug is inserted so that the receptacle terminals will bear upon the plug terminals with a spring pressure, while to prevent accidental removal of the plug and to make better contact, the strips 33 and 34 may have depressions 36 formed therein to receive the bent ends of the receptacle terminals 18 and 19.

The inner ends of the strips 33 and 34 may have threaded holes therein to receive wire clamping screws 37 by which electrical conductors 38 and 39 may be connected to the plug terminals, such conductors extending into the rearward end of the plug B through semi-cylindrical recesses 40 formed in the complementary members 27 and 28. The rearward ends of the members 27 and 28 may be flattened as indicated at 41 to provide finger grips by which the plug may be readily handled, while the forward ends of the members 27 and 28 are preferably constructed as half cones so that when these members are assembled together and the plug is inserted into the receptacle as shown in Fig. 3, the cone-shaped outer surface of the plug will fit snugly within the coned surface of the receptacle body 6.

The extreme outer end of the stem 31 may be rounded off as indicated at 42 to present a smooth surface for engagement with the coned surface 14 of the receptacle so that in inserting the plug into the receptacle all that is necessary is to project the stem against the coned surface of the receptacle and, by reason of the coned surface, the plug stem will automatically find the central or axial bore 15 and thus, irrespective of whether the person can view the receptacle, the alignment of the plug and receptacle may be readily accomplished. The plug terminals 33 and 34 extend on each side of the stem 31 as "keys" to be inserted in the "keyhole" recesses 16 and 17 so that once the stem has been aligned in the bore 15, it is only necessary to press the plug toward the receptacle and to rotate it until the key-like terminals enter the "keyhole" slots 16 and 17. Then the plug may be pressed inwardly of the receptacle with assurance that the plug terminals will be aligned with and will engage the receptacle terminals 18 and 19.

The construction of the receptacle as herein-before described, is relatively inexpensive, since the body portion may readily be formed by any of the well known die molding methods and the terminal strips 18 and 19 may be readily secured thereto in the well known or conventional manner. Likewise the plug may be manufactured inexpensively by die molding the body halves 27 and 28 and merely assembling the terminal strips 33 and 34 thereon. It will be noted that the terminal strips may be secured in place by a single screw for each of them, and that their extension along and in contact with the stem 31 will reinforce these strips, opposing distortion of them due to pressure exerted by the receptacle terminals 18 and 19. The rounded ends of the receptacle terminals 18 and 19, received in the depressions 36 of the plug terminals, will tend to hold the plug in place within the receptacle and avoid accidental removal therefrom.

It will therefore be apparent that I have provided a simple and inexpensive receptacle, the exposed face of which constitutes a funnel-like guiding face which will tend to centralize a plug attempted to be inserted therein, and that I have provided an equally inexpensive construction of a plug having a projecting centralizing stem thereon which will assist in locating the plug in the correct axial alignment with the receptacle and will assist in guiding the terminals of the plug into engagement with the terminals of the receptacle without the necessity of being able to view the receptacle when the plug is being inserted therein.

While for purposes of illustration and description

tion herein, I have shown my plug and receptacle each with two terminals thereon, it will be understood by those skilled in this art that a greater number of radial slots 16 and 17 may be provided, disposed about the central bore 15 while a similar greater number of terminal strips 32 and 33 may be provided upon the plug, permitting a three or more wire connection to be made without departing from the principles of 10 my invention.

While I have shown and described the preferred embodiment of my invention, I do not desire to be limited to any of the details of construction shown or described herein, except as 15 defined in the appended claims.

I claim:

1. An electric circuit connector comprising in combination: a plug including a handle member, a stem projecting outwardly from said handle, 20 a plurality of bevel ended terminals on said handle member projecting outwardly therefrom and radially disposed relative to said stem, and a notch in the outer face of each of said terminals; and a receptacle including a body member having a bore therein for receiving said stem, a cone-shaped depression formed in the front face of said body member with the axis thereof aligned with the axis of said bore for receiving said stem and guiding said plug into alignment with said 25 receptacle, the angle of said cone-shaped depression being substantially equal to the angle at which the ends of said terminals are beveled whereby scratching of the surface of said cone-shaped depression by the ends of said terminals 30 is obviated, a plurality of radially disposed recesses in said body member disposed about said bore and communicating with the surface of said cone-shaped depression and with said bore for receiving said terminals, horizontally disposed 35 resilient terminal connector strips secured to the exterior of said body member and having transversely disposed contacting portions thereof extending into said recesses to enter said plug terminal notches, said contacting portions compris- 40

ing semi-cylindrical portions formed by bending said strip back upon itself on a radius substantially longer than the thickness of said strip.

2. An electric terminal connector comprising in combination: a receptacle including a body 5 portion having a cone-shaped depression formed in the front face thereof, a cylindrical bore in said body portion extending from the apex of said cone-shaped depression and disposed in alignment with the axis thereof, means on said body portion defining a transversely extending opening through said body portion intersecting said bore at a point spaced from said cone-shaped depression, a pair of electric terminals comprising thin strips of resilient metal secured 10 to the exterior of said body extending inwardly into said opening from opposite ends thereof and terminating in a rounded portion formed by bending said resilient material into a semi-cylindrical shape, and a pair of contact receiving slots extending radially outward from opposite sides of said bore extending into communication with the surface of said cone-shaped depression and intersecting said opening; and a plug insertable in said receptacle including a 15 substantially cylindrical handle member, a forwardly projecting cylindrical stem secured to said handle member for reception in said bore, and a pair of electric contact strips carried by said handle member comprising thin strips of 20 metal disposed on edge on opposite sides of said stem for reception in said contact receiving slots when said stem is inserted in said bore, means on said handle securing said contact strips there- 25 to in engagement with said stem, each of said contact strips having a beveled end for engaging said receptacle terminals to wedge the same apart and permit said contact strips to be inserted therebetween, each of said contact strips also including a semi-circular notch for receiving 30 the rounded end of said receptacle terminals to resist movement of said plug out of said receptacle. 35

CHARLES J. SAUNDERS.
